UNITED STATES PATENT OFFICE.

IRVING L. KORROL, OF BROOKLYN, NEW YORK, ASSIGNOR OF ONE-HALF TO DAVID J. MAIBRUNN, OF NEW YORK, N. Y.

CONTAINER TOP.

Application filed October 26, 1927. Serial No. 228,740.

This invention relates to containers for the dispensing of paste, ointments, or other commodities from containers such as collapsible tubes, bottles, or the like, and has particular reference to caps or tops for such containers that are so designed as to eliminate the necessity for screw threaded or other detachable members which are so troublesome because of likelihood of loss from the other parts of the construction, this present invention being in the nature of an improvement over the construction in the co-pending application for container tops, filed June 17th, 1927, Serial No. 199,479.

Among the objects of the invention is to provide a container and a top therefor having correlated features adapted for co-operation of the top with the container in a peculiarly advantageous and dependable manner, the construction being such as to reduce to a minimum the cost of production of the co-operating parts.

A further object of the invention is to provide a container top having a sealing member and peculiar means for connecting the sealing member hingedly to the container neck, the sealing member being adapted to be swung in either direction around the axis of the hinges for delivery of the commodity and to be swung back to sealing position in a substantially airtight condition after the commodity is supplied and where the bulk of the commodity is kept in proper usable condition for the next occasion.

A still further object of the invention is to provide a closure or top structure for a dispensing mechanism which includes a metallic cap or its equivalent carried in internal sealing position for transportation or storage purposes preliminary to use of the commodity and which sealing member is then adapted to be easily removed and discarded.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like

reference characters designate the same parts in the several views, and in which—

Figure 1 is a side elevation of one form of the improvement, full lines showing the sealing member in normal closed position, and in broken lines its position when swung either to the right or left from the normal position.

Fig. 2 is a plan view of the same.

Fig. 3 is a vertical central sectional view on the line 3—3 of Fig. 1.

Fig. 4 is a vertical central sectional view on the line 4—4 of Fig. 2.

Fig. 5 is a view similar in nature to Fig. 1 but showing a modified construction.

Fig. 6 is a plan view of the same.

Fig. 7 is a vertical central section on the line 7—7 of Fig. 5.

Fig. 8 is a vertical central section on the line 8—8 of Fig. 6.

Fig. 9 is a detail perspective view of the sealing member complete as depicted on the second sheet of drawings.

Referring now more specifically to the drawings and to the first set of figures, 10 is a container of any suitable nature or construction for the dispensing of any commodity such as paste or the like, the container being provided with a neck 11. The neck 11 has a delivery port 12 of any suitable cross sectional shape or caliber, and the outer surface of the neck is preferably tapered or frusto conical in form and may be, for the sake of simplicity of construction, unthreaded or smooth. The amount of taper is in excess of the purposes that will appear shortly.

13 is a cap of any suitable material but preferably formed from thin sheet metal and adapted in size and shape to fit directly and snugly upon the smooth exterior surface of the neck 11 and from which it is not supposed to be removed after being once applied thereto. This cap 13 may be described as thimble shaped and with a rounded or spherical outer end 14. In the formation of the cap, the forming dies include a punch for striking out a closure member in the nature of a disk 15, but the press that forms the disk is so designed that after being struck out from the cap the disk is returned immediately to the position shown in Figs. 3 and 4 where it remains

until the commodity is to be used from the container 10 and through the neck 11. The metal from which the cap and disk 15 are formed is so thin that when the commodity 5 is to be used, the person by use of a pin or other sharp instrument, or even a finger nail, may depress one side of the disk, causing it to tilt around a transverse diameter and be lifted out and discarded. While the 10 disk, however, remains in place preliminary to the use of the commodity, the cap is internally sealed, making it impossible for any leakage to take place from the container irrespective of the position in which the 15 container may be placed, stored, or handled.

The primary sealing member above referred to is in the nature of a cap or hood 16 made of any suitable material such as sheet metal and connected by a pair of 20 straps or hangers 17 to pivots 18 on opposite sides of the neck. The hood 16 is so shaped or stamped as to provide a pocket 19 in its center and into which is fitted and secured by any suitable means, such as by friction 25 or glue, a layer of cork 20 or its equivalent, and the general contour of the hood or exterior cap is spherical to conform to the formation of the cap 13 over which it is fitted snugly. The diameter of the cork 20 exceeds that of the opening from which the disk 15 is removable in practice so that the hood and cork members in the practice of 30 the invention constitute a reliable sealing means for the hole through the cap 13.

Any suitable means may be provided for pivoting the hood and hangers 17 to the neck or cap. In this form of the invention there is a ring 21 which carries the pivots 18 and which is adapted to be slipped snugly 35 and permanently upon the lower skirt portion of the cap 13. The parts are so designed that when fitted snugly together in this manner, the axis of the pivots 18 coincides with the center of curvature of the 40 spherical end 14 of the cap, thereby insuring that the exterior cap or hood is free to swing laterally in either direction around the axis of the pivots 18 as shown in Fig. 1, for the opening of the delivery port or ports of 45 the container. When the charge of the commodity is delivered in this manner, the amount delivered is separated cleanly from the bulk remaining in the delivery port, by reason of the fact that the rounded end of 50 the cap is smooth and unobstructed by the outside closure means, and then when the hood is returned to normal position as in Figs. 1 and 2, the exterior surface of the 55 cap is left perfectly clear and the bulk of the commodity is retained in air-tight condition within the cap by virtue of the close 60

fitting hood and gasket or cork closure. It is obvious that in the use of the improvement for the delivery of tooth paste, for instance, the container may be held in 65 either hand and the hood swung over to one side by a finger or thumb of the same hand, while the other hand is used to manipulate the tooth brush, and after the charge is so delivered the same hand holding the container will close the hood without loss of time or without difficulty and especially 70 without the annoyance ordinarily incident to the use of both hands for manipulation of a screw cap or the like. It is pointed out 75 also that from the nature of the cap 13 it is obvious that it may be applied with satisfactory results to a conventional container provided that an external screw thread, although for the most satisfactory results 80 it is preferred that the container and cap structure remain as shown herein to conform to each other.

In the form of the invention shown on the second sheet of drawings, there is provided 85 a ring 21, a hood or cap 16, and a pair of straps or hangers 17 pivoted at 18 substantially identical with those similar features already described, and the container neck 11^a and ring 21 are so designed that the 90 latter fits snugly upon the exterior tapered surface of the neck without the interposition of the thimble cap 13. In this form of the invention instead of employing a discardable disk member 15 in a cap, a corresponding 95 element 15^a is formed and is carried in the outer end of the port 12 of the neck and is removable and discardable in accordance with the practice described in connection with the first set of figures. The hood or 100 external cap structure is constructed and operates the same as before described, including the gasket or cork member 20. The hood 16 in both forms of the invention includes laterally outstanding lips 22 for the 105 easy opening swinging movement of the hood. Either of these lips may be engaged by the finger nail for the purpose of swinging the hood laterally. They assist also in the closing movement of the hood. 110

I claim:

A thin metal container cap for a collapsible tube, said cap having an end and side wall, the end wall having a portion of substantially regular conformation struck therefrom and replaced into said end wall, and a swingable cover for the cap carried by the side wall, said cover being movable snugly over the end wall to protect the said portion thereof. 115

In testimony whereof I affix my signature.
IRVING L. KORROL.
